UNITED STATES PATENT OFFICE.

BENJAMIN F. EATON, OF COXSACKIE, NEW YORK.

SPRING-TEETH FOR HARROWS.

SPECIFICATION forming part of Letters Patent No. 232,119, dated September 14, 1880.

Application filed November 13, 1879.

To all whom it may concern:

Be it known that I, BENJAMIN F. EATON, of Coxsackie, Greene county, in the State of New York, have invented a new and useful Improvement in Spring-Teeth for Harrows, of which the following is a specification.

My invention relates to curved flat spring-teeth for harrows.

The object of my invention is to provide a curved flat spring harrow-tooth with digging-points on each end in such a manner as to render the said tooth serviceable for operating with the soil by either of its ends by reversing the tooth in its frame, and also to stiffen the tooth at its bow, so as to render it capable of resisting excessive strain, and also to provide the digging ends of the tooth with a supplementary duplex point, which may be reversed in its attachment to the tooth as its wear may require.

The invention consists in a curved spring-tooth provided with digging-points at the opposite ends thereof, whereby the tooth may be at any time reversed in its attachment to the frame and either end may be employed for digging.

It also consists in the combination, with a curved spring harrow-tooth, of supplementary digging-points having both ends thereof pointed and adapted to be used as digging-shears.

It finally consists in the combination, with a curved spring harrow-tooth, of an elastic stiffening-piece fitting and secured to the rear side of said tooth, whereby the said tooth will be strengthened against excessive strain.

In the accompanying drawings, in which similar letters of reference indicate like parts, Figure 1 represents a sectional elevation of the harrow-tooth. Fig. 2 is a sectional elevation of the same with the strengthening-piece extended in its upper end. Fig. 3 is a view of the tooth when pointed and before being curved, and Fig. 4 is a perspective view of a tooth provided with a duplex supplementary point.

In the drawings, A is the tooth, which tooth is made of flat spring-steel, and is provided with digging-points *a a'*, one at each end, as shown in Fig. 3. Made in each end, at a short distance back of said digging-points *a* and *a'*, are the holes *x x*, which holes are intended to receive bolts *b*, for the attachment of the tooth

to the frame when the opposite end point is to be used for digging in the soil, and also to receive a bolt, screw, or rivet, *c*, for the attachment of the supplementary digging-point B (shown by full lines in Figs. 1 and 4 and by dotted lines in Fig. 3) to the end of the tooth engaging with the soil.

The supplementary digging-piece B is made of steel and with points *d d*, as shown in Figs. 1 and 4, and is provided with one or more holes for attachment to the digging end of the tooth by rivet *c* or screw or bolt, as may be selected.

The tooth A is stiffened by means of the elastic piece C, made also of flat spring-steel and fitted to the rear side of the tooth and over the bow of the same, as shown in Figs. 1 and 2. This elastic piece may be made with an extension which will fall short of reaching the upper forward end of the tooth, as in Fig. 1, or it may be made to extend to the said upper forward end, as shown in Fig. 2. The said elastic stiffening-piece is secured to the tooth A by bolt *e*, or by a clip, or by rivets, as may be selected.

Holding-spuds and recesses similar to those employed in carriage-springs may also be used for holding the stiffening-piece from working to one side.

D is a beam or bar, made of wood or iron, and forming a part of the harrow-frame, which frame may be made in any form selected. The supplemental duplex point B may be made with the same or with a greater width in its extension from side to side than that of the tooth.

The advantageous results secured by my improved tooth are these: With digging-points made with the opposite ends of the tooth the tooth will be adapted to a reversal of ends, so that when one end becomes worn the tooth may be reversed and the opposite end of the tooth be used for working up the soil, while at the same time the body of the tooth intermediate between the two digging-points of the same will in all cases operate as an elastic standard for carrying the digging-points, which operate as shares when working with the soil, and as the said share-points are about horizontal they will cut away the roots of weeds and grass while they run beneath the surface of the soil, while the soil will be thoroughly stirred by meeting resistance against the con-

cave side of the tooth. By means of the duplex supplementary point B the operator may, when operating with gravelly or stony soil, protect the terminating ends and original digging-points of the tooth from excessive wear, while the said supplementary point may be dispensed with in working with sandy or loamy soil; and when the said supplementary point B is employed the tooth A will operate as an elastic standard and the point be, in fact, a reversible share. It will therefore be readily seen that with the tooth provided with digging-points *a* and *a'* and a duplex supplementary point, B, the tooth will be fitted for enduring at least four times longer than it would were but one point furnished the tooth.

Another advantageous result secured is that the tooth is strengthened at its bow against straightening out under an excessive resistance as the tooth is drawn forward, as in the case of working in sod-soil or meeting an obstruction. By providing the tooth with holes *x x* at about the same relative distance from the ends of the same the same holes will serve as a means for alternately attaching the tooth to the beam D and to the supplementary point B, as occasion may require, and any farmer may make the change in a few minutes by employing a wrench.

I would remark that the side cutting-edges 30 of the digging-points *a a'* of the tooth and *d d* of the supplementary piece B may be made either with a plain line or with a convex or concave form of line, as may be selected.

Having described my invention, what I 35 claim, and desire to secure by Letters Patent, is—

1. Curved spring-tooth A, provided at each end with a digging-point, *a* or *a'*, and having a hole, *x*, near each point, whereby it is adapted 40 to reversal, substantially as set forth.

2. In combination with reversible curved spring-tooth A, the reversible supplementary flat diamond-shaped point B, adapted to attachment to either end of said tooth, substantially 45 as set forth.

3. A reversible spring harrow-tooth having digging-points at each end, substantially as and for the purpose set forth.

4. The curved spring harrow-tooth A, in 50 combination with an elastic stiffening-piece, C, secured to the rear side of said tooth, substantially as and for the purpose set forth.

BENJAMIN F. EATON.
